UNITED STATES PATENT OFFICE

2,159,969

APPLIANCE FOR TESTING THE TENSION OF
TEXTILE THREADS OR YARN

Stefan Fürst, Gladbach-Rheydt, Germany, assignor to W. Schlafhorst & Co., München-Gladbach, Germany, a corporation of Germany

Application December 14, 1937, Serial No. 179,702
In Germany January 12, 1937

3 Claims. (Cl. 265—2)

The invention relates to appliances for testing the tension of a textile thread or yarn while the latter is in action in its machine.

In the case of known appliances of this kind designed to provide a record of the tension of the threads while they are being operated upon it is necessary that the inertia of the mechanism involved should be as small as possible, having regard to the high speeds at which the threads travel. Purely mechanical means have not proved satisfactory and it has therefore been proposed to make tests by electric means, the record of the tension being produced with the aid of a cathode ray or other oscillograph. This method of measurement gives satisfactory results but is expensive. Moreover, such apparatus cannot be so designed as to be handy in use and enable ready access to be had to the different parts.

The object of the invention is to provide an appliance which will combine handiness with sensitiveness and simplicity of design, and it consists essentially of a springy feeler or contact member having a high natural vibration frequency which is adapted to be applied to the thread and has directly fixed thereto a mirror onto which there is projected a beam of light which is deflected to a varying extent in accordance with the movements of the mirror depending on the tension of the thread, and said reflected beam is focused onto travelling light-sensitive paper so that a graph of the tension is produced. The test may be made without interrupting the operation of the thread and at any part of the latter. Optical transmission has been applied to appliances of the kind hereinbefore described, but the reflection was not direct, other transmission means being introduced, which has a detrimental effect on the appliance as regards its sensitiveness and precision, and particularly its simplicity of construction.

Embodiments of the invention are illustrated in the accompanying drawings wherein:

Fig. 1 shows the improved tension tester diagrammatically.

Fig. 2 is a sectional side view of the appliance;

Fig. 3 shows diagrammatically the appliance positioned for application to a thread to be tested.

Fig. 4 shows the parts illustrated in Fig. 3 in testing position, and set for maximum sensitiveness of the apparatus.

Fig. 5 shows a constructional form of apparatus in plan, partly in section, and

Fig. 6 shows by way of example, one method of using the apparatus.

In all the figures 1 designates a source of

light (electric light bulb), 2 a condensing lens, 3 a slit diaphragm, 4 a projection lens, 5 a thread feeler device, and 6 a spring armature for electromagnet 11. A mirror 7 is rigidly fixed to the thread feeler 5, and a mirror 8 is rigidly fixed to spring armature 6. The thread 9 to be tested is guided by the pulleys 10. Part of each beam reflected by the mirrors 7, 8 falls on a deflecting mirror 12 and thence onto visible scale 18 on a ground glass plate 14, and the other part of each beam passes through a plano-convex cylindrical lens 13, by which it is focused onto the light sensitive photographic paper 15. 16 designates a thread tension graph line produced on the paper and 17 a normally continuous base line 15 so long as electromagnet 11 is deenergized. By means, referred to later, a current pulse can be sent through the electromagnet winding, whereby its spring armature is momentarily attracted and thereby momentarily deflects mirror 8 and 20 thus the light beam reflected thereby so that at given intervals kinks are produced in base line 17 as shown, for the purpose to be explained later. Referring to Fig. 2, in casing 19 is disposed a motor 20 which drives through a train of gears 21, 22, 23, 24, 25, 26 a take-up reel 29 arranged to wind up the strip of sensitized paper 15 which passes over a paper guide roller 27 from a supply reel 28. A cover plate 30 provides an air-tight closure for the casing 19. The device 30 is controlled by a trigger lever 31 having a plurality of arms of which one on the right is provided with a rack 32 adapted to engage with a pinion 33, assumed to be connected with gear wheel 22 by a conventional overrunning clutch 35 (not shown), whilst the left arm of the trigger closes contact springs 35, 36 when the trigger is pulled. The purpose of rack 32 is to start motor 20, which is preferably of the non-self-starting synchronous type, by which the speed 40 of paper strip 15 is maintained substantially uniform. Trigger 31 is normally held in inoperative position by a tension spring 34. As shown more clearly in Fig. 5, gear wheel 26 drives a gear wheel 45 which in turn drives the reel 29 through a 45 drag clutch comprising a coil spring 46 disposed between a collar on the hollow hub of pinion 45 and the end of the hub of reel 29. Gear 45 with reel 29 and the reel 28 are carried by screw studs 47 removably disposed in casing 19 to permit 50 exchange of the reels. The source of light 1, the condensing lens 2, the slit diaphragm 3 and the projection lens 4 are mounted in a separate casing 31, disposed within casing 19. The spring feeler 5 and armature 6 are mounted both inside 55

a bush 40 and spring feeler 5 extends into the hollow feeler finger 39 tapering to a point. The guide fingers 38 located on either side of finger 39 contains the pulleys 10. These latter fingers 5 are in shape similar to finger 39. Fingers 38, 39 totally enclose the feeler 5 and pulleys 10 respectively, but for apertures, as shown in Fig. 2, which enable the thread to engage the hook-shaped end (Fig. 1) of feeler 5 and pulleys 10 respectively. The fingers 38 disposed one above and the other below the finger 39 are coupled together and mounted on trunnions carried at the outer end of main casing 19 so that they may be swung together towards or away from the finger 39. Fingers 38 can be differently positioned with respect to finger 39 and the degree of their adjustment is indicated by a pointer 42 biased by a spring 41 and working over a scale 44 on which the pointer can be locked by pin 43 against the 20 tension of spring 41.

The operation of the device is as follows:

The device, as shown in Fig. 6, is slipped for instance onto thread 11 whose tension is to be measured with fingers 38 in the position shown 25 in Figs. 3 and 5, so that the thread can easily enter between fingers 38, 39 as shown in Fig. 3. Then the operator adjusts fingers 38 on scale 44 to the desired relative position with respect to finger 39, according to whether he is testing 30 a high or a low tensioned thread, for instance as shown in Fig. 4. If now trigger 31 is pulled, motor 20 is started as described and switch 35, 36 is closed which supplies current to the motor and lights lamp 1. The beam from the source of 35 light 1 passes through the condensing lens 2, the slit diaphragm 3 and the projection lens 4 and then impinges on the mirrors 7 and 8. The mirror 7 is attached to the thread feeler 5 which flexes to a greater or lesser extent according to 40 the tension of the thread 9 passing over the rollers 10, and in known manner deflects the beam reflected by the mirror. A part of the beam is projected by the obliquely positioned mirror 12 onto the observation plate 14, whilst the re- 45 mainder of the beam passes by mirror 12 and is collected in the lens 13 and focused on the sensitized paper strip 15 at a given point. By moving the photographic paper in the direction of the arrow (Fig. 1) the thread tension graph line 50 16 indicating the varying tension of thread 9 over a given length of its passage through its working machine is produced.

At the same time a beam of light is reflected by mirror 8 of spring 6 partly onto plate 14 and 55 scale 18 (Fig. 1) and partly onto paper strip 15, thus producing first a continuous base line 17. Now if it should be desired to indicate the thread tension between given points in the machine in which the thread is worked and as the thread 60 passes between these points, a contact is made and a circuit is closed thereby into which the energizing winding of electromagnet 11 (Fig. 1) is connected. Every time such a contact is made, spring armature 6 is attracted and thus the light 65 beam reflected by mirror 8 is momentarily deflected and produces one of the kinks shown in base line 17. Such a deflection also becomes visible on scale 18. The contact mechanism by 70 which magnet 11 is energized forms no part of the present invention and is not shown here. It is sufficient to state that the electromagnet 11 provides means by which definite portions or points of the thread relatively to their positions 75 in the working machine can be designated when

the tension graph is produced so that the existing tension at these points can be ascertained.

Fig. 2 shows a particularly handy form of apparatus of pistol-like shape which enables the appliance to be held in one hand. The strip of 5 sensitized paper is wound from the supply reel 28 onto the take-up reel 29 and both reels can be removed by withdrawing the supporting studs 47. The speed of travel of the strip of sensitized paper can be varied by changing the gear 10 wheels 24, 25 for others, these wheels being detachably mounted. The appliance is adapted to be applied to the thread to be tested while the latter is in operation in its working machine so that there is no interruption in the spinning, 15 winding or weaving operation or whatever it may be. Owing to the tapered shape of the fingers 38, 39 the thread will be automatically guided to engage the pulleys 10 and feeler 5 when the appliance is applied to the thread to be tested. The pulleys are mounted in jewel bearings so that they will run easily and with a view to reducing wear.

The degree of sensitiveness of the appliance can be varied by varying the degree of adjustment of the members 38 about their trunnions with consequent variation in the deflection of the thread, such adjustment being indicated by the pointer 42 and scale 44. Fig. 4 shows the maximum deflection of the thread by such adjustment and corresponds to the position 1 on the scale.

What I claim as my invention and desire to secure by Letters Patent of the United States is:

1. An appliance for testing the tension of textile threads while the latter are operated upon, comprising three tension fingers disposed to deflect the thread between them so as to cause the thread to exert its tension against the fingers, a spring feeler of extremely small mass and 40 having a high natural vibration frequency, disposed in the middle finger to contact with the thread to respond to the tension effect of the latter, a mirror directly attached to said feeler, a source of light disposed to project a beam of 45 light onto said mirror so as to be reflected by the latter, and a movable recording screen disposed to receive the reflected beam and means for moving said screen to produce a graph thereon by said beam, corresponding in its rise 50 and fall to the varying tension of the thread.

2. An appliance for testing the tension of textile threads while the latter are operated upon, comprising three tension fingers disposed to deflect the thread between them so as to cause 55 the thread to exert its tension against the fingers, a spring feeler of extremely small mass and having a high natural vibration frequency, disposed in the middle finger to contact with the thread to respond to the tension effect of the latter, a mirror directly attached to said feeler, a source of light disposed to project a beam of light onto said mirror so as to be reflected by the latter, a movable recording screen disposed to receive the reflected beam and means for 60 moving said screen to produce a graph thereon by said beam, corresponding in its rise and fall to the varying tension of the thread, means for reflecting from said light source a second beam onto said screen to normally form a base line 65 coextensive with said graph, and means for actuating said second reflecting means for deflecting said second beam at given points of the thread path to produce marks on said base line 70 so as to indicate by the graph portion between 75

two successive base line marks the tension condition of the thread.

3. An appliance for testing the tension of textile threads while the latter are operated upon, comprising three tension fingers disposed to deflect the thread between them so as to cause the thread to exert its tension against the fingers, said three fingers being pointed at their outer ends to permit the slipping of the fingers onto the thread and the deflection thereof, a thread guide housed in each outer finger and a spring feeler of extremely small mass and having a high natural vibration frequency, disposed in the middle finger to contact with the thread

to respond to the tension effect of the latter, a mirror directly attached to said feeler, a source of light disposed to project a beam of light onto said mirror so as to be reflected by the latter, a movable recording screen disposed to receive the reflected beam and means for moving said screen to produce a graph thereon by said beam, corresponding in its rise and fall to the varying tension of the thread, and means for varying the relative position between the outer fingers and the middle finger to vary the deflection of the thread.

STEFAN FÜRST.
